UNITED STATES PATENT OFFICE.

CHARLES HARRIS DAVENPORT, OF ELK PARK, NORTH CAROLINA, ASSIGNOR TO O. D. HAMRICK AND F. J. KING, BOTH OF ELK PARK, NORTH CAROLINA.

SAW-SET.

1,036,195.

Specification of Letters Patent. Patented Aug. 20, 1912.

Application filed April 15, 1912. Serial No. 690,771.

To all whom it may concern:

Be it known that I, CHARLES HARRIS DAVENPORT, a citizen of the United States, residing at Elk Park, in the county of 5 Mitchell and State of North Carolina, have invented certain new and useful Improvements in Saw-Sets; and I do declare the following to be a full, clear, and exact description of the invention, such as will enable 10 others skilled in the art to which it appertains to make and use the same.

This invention relates to improvements in saw sets.

One object of the invention is to provide 15 a saw set having an improved construction and arrangement of setting mechanism whereby two teeth of the saw will be simultaneously upset in opposite directions and to exactly the same distance and having means 20 whereby the extent of the set of the teeth may be regulated.

Another object is to provide a saw set having an improved means for clamping the device in position on the saw and means 25 for changing the gage of the setting mechanism.

A further object is to provide a saw set 30 which will be simple, strong, and durable in construction, efficient and reliable in operation and well adapted to the purpose for which it is designed.

With these and other objects in view, the 35 invention consists of certain novel features of construction, and the combination and arrangement of parts as will be more fully described and claimed.

In the accompanying drawings; Figure 1 40 is a side view of my improved saw; Fig. 2 is a top plan view thereof; Fig. 3 is a vertical longitudinal section taken on the line 3-3 of Fig. 2; Fig. 4 is a vertical cross section 45 taken on the line 4-4 of Fig. 1; Fig. 5 is a horizontal section taken on the line 5-5 of Fig. 1; Fig. 6 is a perspective view of the 50 supporting frame or casing for the die or anvil blocks.

My improved saw set comprises a central anvil supporting frame or casing 1 which 55 is of rectangular form and is closed on its lower side as shown. In the bottom and sides of the frame is a saw receiving slot 2 with which the blade of the saw is engaged when the device is placed in position thereon. On the ends of the frame or casing 1 are formed channel shaped plunger sup-

porting bars 3 on the ends of which are formed the lower stationary members 4 of a pair of plunger operating handles the upper members 6 of which are pivotally connected at their inner ends to the outer 60 ends of the bars 3 as shown. On the inner ends of the pivoted members 6 of the handles are formed cam projections or offsets 7 which are adapted to engage the outer ends of plunger rods as will be hereinafter more 65 fully described.

Arranged in the frame or casing 1 are die or anvil blocks 8 and 9 against which the teeth of the saw are upset. The blocks 8 and 9 have their upper ends curved or beveled outwardly on their inner sides to form the inclined surfaces against which the saw teeth are upset, and in said blocks are formed transverse passages 10 with which are engaged the inner reduced ends of setting plungers 11 which are disposed in the channel shaped bars 3 of the frame 1 and are slidably engaged with apertures formed in the adjacent ends of the frame and with apertures formed in guide plates 12 arranged in the bars 3 as shown. The outer ends of the plunger rods when thus arranged are in position to be engaged by the cam projections or offsets 7 on the inner ends of the plunger operating members 5 85 of the handles as shown. The plungers 11 are retracted after each operation thereof by the handle members 5 and are held in their retracted positions by coiled springs 13 arranged on the plungers between the 90 ends of the frame and a stop pin 14 arranged through the plungers as shown.

The anvil block 9 is of substantially the same width as the space between the sides of the frame 1, while the block 8 is of less width than said space, and said block 8 is adapted to be adjusted laterally in one direction or the other to bring the passage therein and the end of the plunger engaged with said passage nearer to or farther away from the passage and end of the plunger in the block 9 thereby permitting the ends of the plungers to be adjusted for setting different sizes of saw teeth. The plunger which engages the block 8 has a sufficiently loose connection with the apertures in the end of the compartment and in its guide plate 12 to permit the end of the plunger rod to be shifted by the movement of the block 8. The movement of the block 8 is 100 105 110

effected by means of adjusting screws 15 one of which has a threaded engagement with each side of the frame 1 and has its inner end engaged with the adjacent side of the block so that by screwing one of the screws inwardly and the other outwardly the block 8 may be shifted in the desired direction to adjust the inner end of the plunger rod engaged therewith with respect to the inner end of the plunger rod engaged with the opposing block 9.

The block 9 has on its ends pairs of laterally projecting guide pins 16 which are slidably engaged with pairs of horizontally disposed slots 17 in the opposite sides of the frame 1, and said block 9 is adapted to be shifted in the frame to clamp the saw between the blocks by means of clamping screws 18 which have a threaded engagement with one end of the frame and have their inner ends engaged with the outer side of the block 9 whereby when the screws are turned inwardly, said block will be brought into engagement with the adjacent side of the saw and the latter thereby clamped against the inner side of the opposing block 8.

In order to gage or adjust the set of the teeth by the inner ends of the plunger rods, 30 I provide stop screws 19 which have a threaded engagement with the upper ends of the sides of the frame 1 and have their lower ends projecting into the upper ends of the slot 2 in said sides whereby the distance at which the blade of the saw is permitted to enter the slot is regulated by the engagement of the ends of the screw with the points of the saw teeth. By thus arranging the screws 19 it will be seen that when the device is applied to the saw, the teeth will be permitted to project more or less above the lower side of the inner ends of the plungers or, in other words, the teeth will be exposed to a greater or less extent to the action 40 of the ends of the plungers when forced into engagement therewith thus causing the plungers to upset the teeth to a greater or less extent according to the position at which said ends of the plungers engage the teeth.

In the operation of the device the slot 2 in the frame 1 is engaged with the saw blade and the frame lowered on the blade until the ends of the screws 19 come into engagement with the points of the teeth. When in this position the frame is shifted until two of the teeth are opposite the plunger openings in the blocks 8 and 9 whereupon the clamping screws 18 are tightened up to 55 grip the saw between the blocks as hereinbefore described. After the saw has thus been gripped the handle members are grasped and the upper member forced downwardly toward the lower member thereby causing the offset or cam projections on

the inner ends of said handles to engage the outer ends of the plunger rods thereby forcing the plungers inwardly against the pressure of their retracting springs. This operation of the plungers will project the reduced inner ends thereof through the passages in the blocks 8 and 9 and against the opposite sides of the two adjacent teeth thereby upsetting one of said teeth in one direction against the beveled surface of one of the anvil blocks and the other tooth in the opposite direction against the beveled surface of the opposing block, thus setting the teeth to the same distance as will be readily understood. The reduced tooth engaging ends of the plungers are preferably of triangular shape to correspond with the triangular shape of the saw teeth and the extremities of said reduced ends are formed on an angle as shown.

From the foregoing description taken in connection with the accompanying drawings, the construction and operation of the invention will be readily understood without requiring a more extended explanation.

Various changes in the form, proportion and the minor details of construction may be resorted to without departing from the principle or sacrificing any of the advantages of the invention as claimed.

Having thus described my invention, what I claim is:

1. In a saw set, a central supporting frame, plunger supporting bars arranged thereon, stationary handles projecting from said bars, plunger projecting handles pivotally connected to said bars, tooth setting plungers slidably mounted in said bars, and adapted to be projected by said pivoted handles, anvil blocks arranged in said frame and having their inner upper surfaces beveled or inclined in opposite directions and having therein transversely disposed plunger receiving passages, block adjusting screws arranged in one side of said frame and having their inner ends engaged with the outer side of one of said plunger blocks whereby the latter is adjusted to clamp a saw blade between the same and the opposing block.

2. In a saw set, a central supporting frame having therein a vertical saw receiving slot and having in its sides horizontal guide slots, plunger supporting bars arranged on the ends of said frame, stationary handles on the ends of said bars, plunger projecting handles pivotally connected to the bars, spring retracted plungers having reduced tooth engaging inner ends, anvil blocks arranged in said frame and having therein transverse plunger receiving passages, guide pins arranged on the ends of one of said blocks and having a sliding engagement with the guide slots in said frame, block adjusting screws having a threaded

engagement with one end of the frame and having their inner ends engaged with said block whereby the latter is adjusted to clamp a saw blade between the same and the opposing block, and means whereby the opposing block is adjusted to regulate the distance between the inner ends of the plungers engaged with the passages in the blocks to set different sizes of saw teeth.

5 3. In a saw set, a central supporting frame, plunger supporting bars arranged on and projecting from said frame, stationary handles on the ends of said bars, plunger operating handles pivotally connected to the latter, anvil blocks arranged in said frame and having therein plunger receiving passages, spring retracted plungers slidably mounted in said bars and having their inner ends engaged with the passages in said 10 anvil blocks, plunger projecting offsets on said plunger operating handles to project said plungers through said anvil blocks and into engagement with the teeth of the saw engaged between the blocks, means whereby 15 one of said blocks is adjusted to bring the end of the plunger engaged therewith nearer to or farther from the end of the plunger engaged with the opposing block, and means to adjust the other block whereby the blade 20 of the saw is clamped and held in position between said blocks.

4. In a saw set a central supporting frame having therein a saw receiving slot, plunger supporting bars arranged on the ends thereof, stationary handles on said bars, 35 plunger projecting handles pivotally connected to the latter, plungers slidably mounted in said bars, anvil blocks arranged in said frame and having therethrough plunger receiving passages, one of said 40 blocks being of less width than the width of the frame, means whereby said block is adjusted to vary the distance between the plunger receiving passage therein and the plunger receiving passage on the opposing block 45 whereby the ends of the plungers are spaced a greater or less distance apart for setting teeth of different size and gage screws arranged in the upper edges of the sides of 50 said frame and having their inner ends projecting into the upper ends of said saw receiving slot whereby the engagement of the frame with the saw blade is regulated and the set of the saw teeth by the inner ends of the plungers is gaged.

55 In testimony whereof I have hereunto set my hand in presence of two subscribing witnesses.

CHARLES HARRIS DAVENPORT.
